UNITED STATES PATENT OFFICE

LOUIS M. PEARCE, OF HOUSTON, TEXAS, ASSIGNOR TO TEXAS IRON WORKS SALES CORPORATION, OF HOUSTON, TEXAS, A CORPORATION OF TEXAS

TUBING SLIP

Application filed June 1, 1929. Serial No. 367,800.

This invention relates to new and useful improvements in a tubing slip.

One object of the invention is to provide a device of the character described specially adapted to be mounted on a rotary table or casing head, and designed to engage and hold tubing suspended in a well bore, and which is of such construction that it may be easily applied to or released from a tubing in the well.

Another object of the invention is to provide a tubing slip of such novel formation that it will firmly grip and hold the tubing suspended but will not bite into or injure said tubing and the invention further comprehends a novel construction which will be effective to permit the release of the tubing by the slip upon upward movement of said tubing, to the end that the slip will not grip and hold the tubing upon upward movement thereof, but will readily release the same.

The invention further comprehends a novel type of releasing ring mounted in the adapter in a novel manner.

With the above and other objects in view the invention has particular relation to certain novel features of construction, operation and arrangement of parts, an example of which is described in this specification and illustrated in the accompanying drawing, wherein:

Figure 1 shows a plan view of the slip.

Figure 2 shows a transverse sectional view taken on the line 2—2 of Figure 3.

Figure 3 shows a vertical sectional view taken on the line 3—3 of Figure 1, and

Figure 4 shows a fragmentary vertical sectional view taken on the line 4—4 of Figure 2.

Referring now more particularly to the drawings, wherein like numerals of reference designate similar parts in each of the figures, the numeral 1 designates a sectional adapter formed preferably of two sections, arcuate in horizontal cross sectional contour. These sections are hinged together at one side, by the hinge 2, and opposite said hinge one of said sections is formed with spaced bearing members 3, 3 and the other with an ear 4, to fit between said bearing members. Said

bearing members and ear having vertical openings which align when the adapter is in closed position to receive a lock pin 5.

The adapter may be opened, or its sections swung apart, on the hinge 2. The adapter has a substantially smooth under surface so that it may be seated on a rotary table, casing head or other suitable support.

Each section of the adapter has the upper and lower inwardly extending flanges 6, 7 spaced apart. That portion 9 of the inner side of each adapter section, between said flanges, tapers or converges downwardly. There is a sectional releasing ring preferably composed of four sections indicated by the numerals 8. These sections are arcuate in horizontal cross sectional contour and are located between the upper and lower flanges 6 and 7 and work against the downwardly converging seat 9 of the adapter and the outer sides of the ring sections converge downwardly to conform to the taper of said converging seat 9 of said adapter 1. Each section 8 of the releasing ring has a limited vertical movement between the flanges 6, 7. Each ring section 8 has a vertical bore 10 therethrough, and there are bearing rods 11 which are fitted upwardly through the adapter and through said bearings 10. The lower end 12 of each rod 11 is enlarged and externally threaded and screwed into said adapter and the upper end of each rod, is seated in a socket 13, in the underside of the flange 6. The bearings 10 are of a greater diameter than the corresponding rods 11 to permit a vertical as well as a lateral movement of the sections 8 relative to the adapter.

The inner sides of the releasing ring sections converge downwardly having a somewhat greater pitch than the pitch of the seat 9 of the adapter and forming a downwardly converging seat 14, for the slip jaws 15, 15'. There are preferably three of these jaws, each arcuate in horizontal cross sectional contour and when assembled they form a complete tubing holding slip whose outer side tapers downwardly to conform to the taper of the seat 14 and when seated in the said seat 14 of the releasing ring they will securely grip and hold the tubing 16 therein. The inner

sides of these jaws have transverse grooves 17, spaced apart forming pockets and between said grooves the jaws may be provided with blank faces 18 which contact against and grip the tubing to be held. By reason of the decided pitch of the seat 14 these gripping or friction faces 18 will securely grip and hold the tubing, by friction, without biting into and weakening it. The grooves or pockets 17 are provided to receive the paraffin 10 mud or other coating on the pipe or tubing to be held and this coating will be forced into these pockets so that the faces 18 may frictionally engage the metal of the tubing to the end that the tubing will not slip down through the slip jaws.

Fastened rigidly to the intermediate jaw 15' there is a handle 19 and opposite this handle there are the manipulating handles 20, 20. The outer ends of the handles 19, 20 are formed with suitable grips and the inner ends of the handles 20 are formed arcuate and are seated loosely in outside, arcuate grooves 21, 21 of the jaws 15 with their extreme inner ends fitted loosely in the sockets in the opposite sides of the intermediate slip jaw 15'. These handles are secured to the respective jaws by means of bearing pins as 22 which are fitted downwardly through suitable holes in the upper ends of the slip jaws and through bearings in said handles provided to receive them and the lower ends of said pins are screwed into said jaws. The bearings as 23 of the handles 20 are oblong so as 35 to permit relative free movement of said jaws with the respect to the handles and with the respect to each other to the end that they will readily release the pipe when the pipe or tubing is pulled upwardly to unseat the slip jaws 40 from the releasing ring.

In making up string of tubing the slips are engaged around the upper end of the string suspended in the bore and when an additional joint of tubing is screwed on the upper end 45 of the string, said string as thus completed is elevated carrying the jaws 15, 15' upwardly with it, and when the jaws clear the upper end of the releasing ring 8 a workman may grip the handle 19 and suddenly pull said 50 jaws outwardly clear of the pipe and rest said jaws on the rotary table or casing head in readiness to be again applied to the tubing. The entire string is then lowered until its upper end is opposite said jaws, and the workman may then grip the handles 20 and seat the slip jaws in the seat 14 in tubing holding position around the tubing.

In breaking up a string of tubing the upper joint to be unscrewed extends above the tubing or casing head with the holder in engagement with the string beneath the joint. When the joint is unscrewed, and removed the string is elevated carrying the slip jaws upwardly with it until they clear the releasing ring, and release the string, and they are

held in readiness to be reengaged, around said string beneath the next joint to be removed, and at the proper time are so engaged and seated in the seat 14 of the releasing ring as above explained until another joint 70 of the string is removed and so on until the string is completely broken up and removed.

When an upward pull is exerted on the tubing held by the holder as above explained the releasing ring 8 will readily move upwardly with the slip jaws relative to the adapter by reason of the slow taper of the seat 9 and this movement of said ring will result in the quick release of the slip jaws, which wedge very tightly around the tubing 75 by reason of the fast taper of the seat 14.

A preferred form of the invention has been shown and described, by way of illustration only, while the broad principle of the invention will be defined by the appended claims. 80

What I claim is:

1. In a tubing slip an adapter formed of two arcuate sections, hinged together at one side, means for detachably securing the sections together at the other side, the inner side of each section having an upper and lower, inwardly extending flange and having a downwardly converging surface between said flanges, a releasing ring within the adapter formed of sections whose outer surfaces converge downwardly at a pitch corresponding to the pitch of the inside of the adapter, the upper ends of the ring sections being normally spaced beneath said upper flange, each section of the said ring having a bearing therethrough and bearing rods of less diameter than that of said bearings anchored to the adapter and extending through said bearings. 90

2. In a tubing slip an adapter formed of two sections hinged together at one side, means for detachably securing the sections together at the other side, the inner side of said sections converging downwardly forming a seat, a releasing ring within the adapter whose upper end is normally spaced beneath the opposing part of the adapter, said releasing ring being formed of sections whose outer surfaces converge downwardly at a pitch corresponding to the pitch of said seat, each section of said releasing ring having a vertical bearing therethrough and bearing rods of less diameter than that of said bearings extending through the bearings and anchored to the adapter. 100

3. In a tubing holder, an adapter formed of two confronting arcuate sections, the inner side of each section having an upper and a lower inwardly extending flange and having a downwardly converging seat between said flanges, a releasing ring within the adapter whose upper end is normally spaced beneath said upper flange, said ring being formed of sections whose outer surfaces converge downwardly at a pitch corresponding 110

115

130

with the pitch of said seat, each section of said releasing ring having a vertical bearing therethrough and bearing rods of less diameter than that of said bearings extending through said bearings and anchored to the adapter.

4. In a slip an adapter formed of two arculate sections whose inner surfaces taper downwardly forming a seat, a releasing ring
10 within the adapter and of less height than said seat and formed of sections whose outer surfaces converge downwardly at a pitch corresponding to the pitch of the inside of the adapter, each section of the ring having
15 a vertical bearing and bearing rods secured to the adapter and passing through said bearings each rod having a diameter less than that of the corresponding bearing.
5. In a slip an adapter formed of sections
20 whose inner surfaces taper downwardly, a sectional releasing ring within the adapter, the outer surfaces of whose sections taper downwardly at a pitch which substantially corresponds to the pitch of the inside of the
25 adapter, the upper ends of the ring sections being normally spaced beneath the opposing parts of the adapter sections, means securing the ring sections loosely to the adapter, said securing means permitting the ring sections
30 to freely move vertically and radially in the adapter.

In testimony whereof I have signed my name to this specification.

LOUIS M. PEARCE.
